UNITED STATES PATENT OFFICE.

LOU MITCHELL CORBIN, OF MACON, MISSOURI.

TWINE-HOLDER.

No. 796,298.

Specification of Letters Patent.

Patented Aug. 1, 1905.

Application filed August 28, 1904. Serial No. 221,868.

To all whom it may concern:

Be it known that I, LOU MITCHELL CORBIN, a citizen of the United States, residing at Macon, in the county of Macon and State of Missouri, have invented a new and useful Twine-Holder, of which the following is a specification.

The invention relates to improvements in twine-holders.

The object of the present invention is to improve the construction of twine-holders and to provide a simple, inexpensive, and efficient device adapted to be placed on a shelf or other support at an elevation and at a point remote from the counter and capable of ready adjustment to arrange the free end of the twine over the counter or at any other desired point.

A further object of the invention is to provide a twine-holder of this character adapted to enable the twine or cord to be freely unwound from a spool or cone and capable of effectually preventing the same from becoming caught or tangled.

With these and other objects in view the invention consists in the construction and novel combination and arrangement of parts, hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a perspective view of a twine-holder constructed in accordance with this invention. Fig. 2 is a side elevation, partly in section. Fig. 3 is a horizontal sectional view on the line 3 3 of Fig. 2. Fig. 4 is an enlarged detail perspective view of the top bar which constitutes the inner section of the extensible arm of the twine-holder. Fig. 5 is a detail sectional view on the line 5 5 of Fig. 2. Fig. 6 is a detail sectional view illustrating the construction of the telescopic sections of the extensible twine-supporting arm.

Like numerals of reference designate corresponding parts in all the figures of the drawings.

1 designates a frame composed of a base 2, front and rear standards 3 and 4, and a top bar 5, which constitutes the innermost section of an extensible twine-receiving arm, which is supported by the frame and which is

adapted to be adjusted to cause the free end 6 of a spool or cone of twine to be arranged over a counter or at any other convenient point at a distance from the spool or cone. The frame, which is preferably constructed of cast metal, may be made of any other desired material, and the base, which is preferably provided with an enlarged central circular portion, is designed to be secured by screws 7 to the supporting-surface, suitable perforations being provided for the screws, as indicated in Fig. 3 of the drawings. The frame may be conveniently placed upon the top of a row of shelving, as indicated in Fig. 1 of the drawings, or it may be placed on any one of the shelves or upon any other suitable support, as will be readily understood. The base of the frame is also provided with a vertically-disposed cone 8, preferably hollow, as shown, and adapted to receive the twine, which is fitted on the cone and which is unwound therefrom without rotating the entire mass of cord or twine.

The top bar is provided at a point directly above the cone with a guide-opening 9 for the twine, which extends through the top bar at that point, whereby when the twine is pulled it readily unwinds from the ball or cone without rotating the same. The front portion of the top is enlarged, as clearly shown in Figs. 2 and 4 of the drawings, and is provided with a longitudinal groove 10, having a flat bottom and inwardly and upwardly inclined side walls and adapted to receive an intermediate telescoping section 11, which is substantially trough-shaped, being composed of a flat bottom and upwardly and inwardly inclined side walls 12, which form a groove or way similar in shape to the groove of the top bar 5, but of less diameter than the same. The innermost section receives a substantially trough-shaped outer section 13, which is also composed of a flat bottom and inwardly-inclined side walls. By this construction the sections are slidably interlocked and are adapted to telescope or slide on one another, and they form an extensible arm, which is adapted to project any distance within the capacity of the device to support the free end of the twine at a convenient point and to enable the mass of cord or twine to be arranged out of the way and in convenient position for renewing the twine when the same is consumed. The top bar 5 is provided at the inner end of the longitudinal groove 10 with a guide-notch 14 to receive the twine, which ex-

tends through the hollow sections, the grooves performing the double function of slidably receiving the sections and the twine, which is thereby guided to the outer end of the outermost section and is effectually prevented from becoming caught or tangled. The outermost section is provided near its outer end with a guide-opening 15, through which the twine passes. By this construction the twine may be readily unwound or unreeled from the cone or spool at a considerable distance beyond the same. Any number of telescoping sections may be provided, and the sections may be constructed of any desired length. When a cone or ball of twine is consumed, a new ball or cone may be readily placed in the frame and may be quickly threaded through the extensible arm for use.

Having thus fully described my invention, what I claim as new, and desire to secure by Letters Patent, is—

1. A twine-holder provided with an extensible twine receiving and guiding arm having a longitudinal groove for the twine.

2. A twine-holder, comprising a frame having a twine-receiving base provided with means for mounting it on a support, twine-receiving means carried by the base, and an arm arranged at the top of the frame and provided with a longitudinal groove, said arm being also provided at a point above the twine-receiving means with a guide-opening for the twine.

3. In a twine-holder, the combination with twine-receiving means, of front and rear standards, and a twine-receiving arm supported by the standards and extending beyond the same and provided with a longitudinal twine-receiving guide or way extending to the outer end of the arm.

4. A twine-holder, comprising a frame having front and rear standards and provided with a connecting-base, twine-receiving means mounted on the base and extending upward therefrom, and a twine-receiving arm connecting the standards and extending beyond the same and provided above the twine-receiving means with a guide-opening, said arm being also provided in advance of the guide-opening with a longitudinal groove forming a guide or way for the twine and extending to the outer end of the arm.

5. A twine-holder, comprising a frame hav-

ing front and rear standards and provided with a connecting-base, twine-receiving means mounted on the base and extending upward therefrom, and a twine-receiving arm connecting the standards and provided above the twine-receiving means with a guide-opening, said arm being also provided in advance of the guide-opening with a longitudinal groove and having a guide-notch at the rear end of the groove.

6. A twine-holder provided with an extensible arm embodying an inner section having a longitudinal groove, and a movable section slidable in the groove and provided with a corresponding groove, said grooves also forming guides for the twine.

7. A twine-holder provided with an extensible arm embodying an inner section provided throughout a portion of its length with a longitudinal groove having upwardly and inwardly inclined side walls, and a slidable section fitting within the said groove and having upwardly and inwardly inclined side walls forming a groove, said grooves being adapted to receive the twine.

8. A twine-holder provided with an extensible arm embodying an inner section provided with a longitudinal groove having inwardly and upwardly inclined side walls, said inner section being also provided with a guide located beyond the groove, and a plurality of slidable sections telescoping within the said groove and having upwardly and inwardly inclined side walls, one of the sections being provided at its outer end with a guide.

9. A twine-holder, comprising a frame having a twine-receiving base and provided at the top with a fixed section having a longitudinal groove, said fixed section being also provided beyond the groove with a guide-opening for the twine, and a plurality of slidable sections having grooves and arranged in the groove of the fixed section, one of the slidable sections being also provided with a guide-opening for the twine.

In testimony that I claim the foregoing as my own I have hereto affixed my signature in the presence of two witnesses.

LOU MITCHELL CORBIN.
